BASE FOR A TELEPHONE HANDSET

Robert E. Wirsching, Greenfield, Ind., assignor to Bell Telephone Laboratories, Incorporated, New York, N.Y., a corporation of New York

Filed Dec. 29, 1961, Ser. No. 68,121

Term of patent 14 years

(Cl. D26—14)

FIG. 1

FIG. 3

FIG. 1 is a perspective view of a base for a telephone handset showing my new design;

FIG. 2 is a front elevational view thereof; and

FIG. 3 is a side elevational view.

The essential features of my design are shown in full line, and the dial, shown in broken line, is for illustrative purposes only.

I claim:

The ornamental design for a base for a telephone handset, substantially as shown and described.
